UNITED STATES PATENT OFFICE.

EDWARD W. FISHBURNE, OF RICHMOND, VIRGINIA, ASSIGNOR OF THREE-SIXTHS TO AUGUST MEYER, TWO-SIXTHS TO THOMAS B. LEONARD, AND ONE-SIXTH TO JOHN ASKIN, ALL OF RICHMOND, VIRGINIA.

SHADE-HANGER.

1,143,263.

Specification of Letters Patent. Patented June 15, 1915.

Application filed July 25, 1914. Serial No. 853,135.

To all whom it may concern:

Be it known that I, EDWARD W. FISHBURNE, a citizen of the United States, residing at Richmond, in the county of Henrico and State of Virginia, have invented certain new and useful Improvements in Shade-Hangers, of which the following is a specification, reference being had to the accompanying drawings.

10 This invention relates to certain improvements in shade hangers and has relation more particularly to a device of this general character wherein the roller is capable of vertical adjustment relative to the window frame with which the hanger is employed; and an object of the invention is to provide a device of this general character having novel and improved means whereby the hanger may be applied into operative position with convenience and facility and whereby a shade roller may be effectively engaged.

25 Furthermore, it is an object of the invention to provide a novel and improved device of this general character comprising a plurality of fixtures slidably supported by suitable guides and whereby said fixtures are suitably engaged to adjust the same relative to the guides.

30 The invention also has for its object to provide a novel and improved device of this general character wherein a plurality of shade rollers may be operatively supported one in advance of the other and capable of simultaneous adjustment relative to the window frame with which they are employed.

The invention consists in the details of construction and in the combination and arrangement of the several parts of my improved shade hanger whereby certain important advantages are attained and the device is rendered simpler, less expensive and otherwise more convenient and advantageous for use, all as will be hereinafter more fully set forth.

45 The novel features of the invention will be carefully defined in the appended claim.

In order that my invention may be the better understood, I will now proceed to describe the same with reference to the accompanying drawings, wherein—

50 Figure 1 is a front elevational view, showing a hanger constructed in accordance with an embodiment of my invention in applied

position; Fig. 2 is a side elevational view of the invention as disclosed in Fig. 1; Fig. 3 is a detail section on the line 3—3 of Fig. 1; Fig. 4 is a perspective view of a barrel herein included; and Fig. 5 is a detail sectional view of a lower bracket herein embodied. 60

As disclosed in the accompanying drawings, A denotes a window frame of any ordinary or preferred construction having suitably secured thereto at opposite sides thereof, the vertically aligned upper brackets 1 65 and lower brackets 2.

Each of the upper brackets 1 comprises a base plate 3, having projected from its under surface the screw element 4 integrally produced therewith and whereby said plate 70 is operatively engaged with the window frame. Projecting forwardly from the plate 3 is a shank 5 of predetermined length and terminating in an elongated head 6 disposed longitudinally in the same general direction as the longitudinal axis of the plate 3 and integrally produced with such shank. The upper portion of the head is provided with the transverse opening 7 disposed perpendicularly to the shank 5 and in which is 80 rotatably supported, through the medium of the pin 8, the pulley 9, for a purpose to be hereinafter more fully set forth.

As herein embodied, the pin 8 has its inner extremity threaded and adapted to be received within a similarly threaded cavity 10 disposed longitudinally of the shank 5 and through the end portion of the head 6. In order that the pin 8 may be applied or removed with convenience and facility, I find 85 it of advantage to have the outer extremity or head thereof provided with the groove 12 in order to permit a screw-driver or similar implement to operatively engage the same in a manner which is believed to be self-evident. 90

The lower end of each of the heads 6 is provided with the longitudinally disposed threaded recess 14 adapted to receive the threaded extremity 15 of an elongated guide 100 rod 16 loosely disposed through an opening 17 produced in the outer extremity of the shank 18 of a lower bracket 2, said bracket being in predetermined spaced relation relative to the upper bracket 1. As herein embodied, the shank 18 is integrally produced with the plate 20 and such plate 20 is provided with the screw member 21 disposed in 105

a direction opposite to the shank 18 and adapted to afford a means whereby said bracket 2 may be operatively engaged with the frame A.

5 Loosely surrounding each of the guide rods 16 is a sleeve or barrel 22 capable of sliding movement longitudinally of such guide rod and, as herein embodied, said barrel is provided with the oppositely directed 10 arms 23 disposed perpendicularly of the frame A when in applied position, and the free extremities of each of such arms 23 are provided with the openings 24 to afford the requisite means whereby the shade rollers 15 R may be operatively supported thereby and maintained in spaced relation one in advance of the other, and it is to be observed that the rearwardly disposed arms 23 terminate in close proximity to the outer face of 20 the frame A, although I do not wish to be understood as particularly limiting myself to this latter arrangement but I have found the same to prove of advantage in practice.

The barrels 22, as herein embodied, are 25 provided with the perforate ears 25 projecting in the same general direction and affording a means whereby the extremities of a flexible member 26 may be operatively engaged with the barrels, the strands of said 30 members being disposed around the pulleys 29, one of such pulleys being of a double type, for a purpose which is believed to be clearly obvious to those skilled in the art to which my present invention appertains. 35 Suitably engaged with the flexible member 26 and to the portion thereof projected through the head provided with the double pulley is the operating cord 27 and serving as a medium whereby the barrels 22 may be 40 adjusted upwardly of the guide rods 16, it being understood that the movement of the barrels in the opposite direction is created by gravity.

In order to maintain the barrels 22 in 45 their varying adjusted positions, I secure at a predetermined point upon the frame A a retaining member 28 adapted to be engaged by the cord 27, as is believed to be self-evident.

50 It is to be observed that my improved hanger comprises a minimum of parts and, in addition to serving as a guide, it is to be

observed that the rods 16 maintain the arms 23 of the barrels 22 in effective engagement with the shade rollers. When it is desired 55 to remove or replace a roller, it will be observed that it is only necessary to disengage one of the rods 16 from its coacting head. In order that the rod may be engaged or disengaged from its head with convenience 60 and facility, I find it of advantage to provide the lower end of each of the rods 16 with the groove 29 in order that a screwdriver or the like may be conveniently engaged therewith for imparting the requisite 65 axial rotation thereto.

From the foregoing description, it is thought to be obvious that a shade hanger constructed in accordance with my invention is of an extremely simple and comparatively inexpensive nature and is particularly well adapted for use by reason of the convenience and facility with which it may be assembled, and it will also be obvious that my invention is susceptible of some change 70 and modification without material departure from the principles and spirit thereof and for this reason I do not wish to be understood as limiting myself to the precise 75 arrangement and formation of the several 80 parts herein shown in carrying out my invention in practice.

I claim:

A device of the character described comprising vertically spaced brackets, guide rods operatively supported by the brackets, a barrel slidably mounted on each of the rods, arms carried by the barrels and projecting laterally therefrom midway the length thereof, the extremities whereof being provided with roller engaging means, a perforate ear carried by each barrel and projecting therefrom in the same general direction, and means engageable with the perforate ears coacting with the upper brackets 85 for imparting movement to the barrels in one direction.

In testimony whereof I hereunto affix my signature in the presence of two witnesses:

EDWARD W. FISHBURNE.

Witnesses:

JOHN H. MASSIE,
F. P. RYOM.
